UNITED STATES PATENT OFFICE.

LEE C. HOUNSELL, OF GALENA, ILLINOIS.

LIFTING DEVICE FOR AUTOMOBILES.

Application filed March 9, 1926. Serial No. 93,474.

This invention relates to a device adapted for facilitating the lifting of the front ends of automobiles and particularly those of the Ford type wherein the hand engine starter 5 crank is permanently associated with the front end of the vehicle.

The primary object of the invention is to provide a device that is adapted for attachment to the starter crank in order that a 10 hook upon one end of a hoisting cable may be attached thereto in order that the front end of the machine may be raised for the attachment or removal of the front springs thereof.

15 A further object of the invention is to provide a device of this character that is extremely simple of construction, and that is of such a nature as to be so associated with said hand crank as to be positively associated therewith when the hook of the hoisting cable has been connected thereto for 20 overcoming any liability of the machine dropping while in suspended condition.

Other objects will become apparent as the 25 nature of the invention will be better understood, the same comprising the novel form, combination, and arrangement of parts hereinafter more fully described, shown in the accompanying drawing and claimed.

30 In the drawing wherein like reference characters indicate corresponding parts throughout both of the views:

Figure 1 is a view in fragmentary front elevation of the Ford type automobile with 35 the engine starting hand crank of which has been applied my improved lifting device, and

Figure 2 is a rear elevation of the device per se.

40 Now having particular reference to the drawing, 5 indicates fragmentarily the front end of a Ford or other automobile with which the engine starting hand crank 6 is permanently attached which crank is in 45 the form of a rod, the free end of which is bent outwardly at right angles to provide a handle 7.

My device constitutes the provision of a metal casting that is in the form of a heavy 50 plate 8 that is formed centrally with an opening 9 adapted for receiving the handle portion 7 of said crank 6 as clearly shown in Figure 1. The upper end of this casting is formed with a hook receiving ring 9 with 55 in which is to be engaged a hook 10 upon one end of a hoisting cable 11, Figure 1.

At the lower end of the plate is a square shaped extension pin 12 to the opposite sides of which are pivotally connected the legs of a U-shaped clevis 13, that will when swung upwardly upon the back side of the plate engage over the opening 9 therein as clearly shown in Figure 2, and it is in this position of the clevis that said plate is arranged upon the handle portion 7 of the crank 6, after which said clevis is allowed to drop downwardly at right angles upon the main portion of the crank as clearly shown in Figure 1, which will prevent the withdrawal of the device therefrom in an obvious manner.

It will thus be seen that I have provided a highly novel, simple, but yet efficient device for facilitating the hoisting of the front end of a Ford or other type of automobile that is provided with a permanently attached engine starting hand crank, and even though I have herein shown and described the most preferred embodiments of the invention with which I am at this time familiar, it is nevertheless to be understood 75 that modifications may be had without effecting the spirit and scope of the appended claims.

Having thus described the invention, what I claim as new and desire to secure by Letters Patent is:—

1. In a lifting device of the class described, an automobile crank handle engaging plate, said plate having an opening for receiving the handle portion of the crank 90 and having means for attachment to a hoisting mechanism, means for locking the plate on the handle portion of the crank, said means comprising a member pivoted to the plate for engagement around the crank beneath the handle portion thereof.

2. In a lifting device of the class described, an automobile crank engaging member comprising a plate having an opening therein for receiving the handle portion of the crank and adapted for attachment to a hoisting mechanism, and a clevis pivoted to the plate beneath the opening for engagement around the crank beneath the handle portion therefor for securing the plate thereon.

3. In a lifting device of the class described, a member adapted for attachment to a hoisting mechanism, said member having an opening provided therein receiving the handle portion of an automobile crank, and an additional member pivoted to the

10
aforementioned member adapted for engagement around the crank beneath the handle portion for securing the first mentioned member thereon.

15
5. 4. In a lifting device of the class described, an automobile crank engaging member comprising a plate having an opening therein for receiving the handle portion of the crank, a ring associated with the upper

portion of said plate for facilitating the attachment of the plate to a hoisting mechanism, an extension pin formed on the lower portion of said plate, and a clevis pivoted to the pin and adapted for engagement around the crank beneath the handle portion for 15 securing the plate thereon.

In testimony whereof I affix my signature.
LEE C. HOUNSELL.
